(57) **CLAIM**

The ornamental design for a stairway bench, as shown and described.

DESCRIPTION

FIG. 1 is a perspective view of a stairway bench showing my new design;

FIG. 2 is a side elevational view thereof;

FIG. 3 is an elevational view of the opposite side thereof;
FIG. 4 is an end view looking from the left with respect to FIG. 1;

FIG. 5 is an end view looking from the right with respect to FIG. 1;

FIG. 6 is a top plan view thereof;

FIG. 7 is a bottom plan view thereof;

FIG. 8 is a perspective view showing my stairway bench in collapsed position;

FIG. 9 is a perspective view showing one mode of operation of my stairway bench on a stairway; and,

FIG. 10 is a perspective view showing a second mode of operation of my stairway bench on a stairway.

The portions shown in broken lines in FIGS. 9 and 10 are for information only and form no part of the claimed design.
